UNITED STATES PATENT OFFICE.

CHARLES L. SLADINSKA, OF FOUNTAIN CITY, WISCONSIN.

BEET-HARVESTER.

1,067,884.

Specification of Letters Patent.

Patented July 22, 1913.

Application filed September 28, 1911. Serial No. 651,870.

To all whom it may concern:

Be it known that I, CHARLES L. SLADINSKA, a citizen of the United States, residing at Fountain City, in the county of Buffalo, 5 State of Wisconsin, have invented certain new and useful Improvements in Beet-Harvesters; and I do hereby declare the following to be a full, clear, and exact description of the invention, such as will enable others 10 skilled in the art to which it appertains to make and use the same.

This invention relates to beet harvesters.

An object of the invention is to provide a beet harvester having a tilting carrier for 15 gripping the leaves of the beets uprooted by the plows, novel means being employed for guiding the carrier in its tilting movement, and further novel means being employed for causing the endless gripping blades of the 20 carrier to securely grip the leaves regardless of the density of the foliage.

With the above object in view the invention consists in certain novel details of construction and combination of parts herein- 25 after fully described and claimed, it being understood that various modifications may be made in the minor details of construction within the scope of the appended claims.

In the accompanying drawings forming 30 part of this specification: Figure 1 is a plan view of the beet harvester. Fig. 2 is a side elevation of the beet harvester. Fig. 3 is a longitudinal sectional view through the beet harvester. Fig. 4 is a cross sectional view 35 taken on the line 4—4 Fig. 2. Fig. 5 is an enlarged cross sectional view taken on the line 5—5 of Fig. 2. Fig. 6 is a fragmentary sectional view taken on the line 6—6 Fig. 2 showing arcuate guides for the carrier. Fig. 40 7 is a cross sectional view taken on the line 7—7 of Fig. 2. Fig. 8 is a plan view of the carrier base plate.

Referring now to the drawings in which like characters of reference designate similar parts, 10 designates an axle the outer ends of which are equipped with ground wheels 11. The wheels are loose on the axle, and to the hub of one of the wheels a clutch sleeve 12 is fixed, the clutch sleeve having a 45 serrated face which contacts with a similar face of the hub 13 of a loose driving gear 14 carried upon the axle. The axle is arched centrally in the form of an inverted U as shown at 15.

50 The main frame consists of parallel horizontal floor bars 16 secured to the outer sides

of the arch, and the rear ends of which are inclined downwardly as shown at 17. The floor bars are connected adjacent to their forward ends by cross beams 18 preferably 60 three in number. L-shaped hangers 19 are loosely mounted at their upper ends on the axle, and to the vertical legs of these hangers are bolted rearwardly extending angle iron bars 20 the rear ends of which are 65 bolted to the lower ends of the inclined portions 17 of the floor bars. The hangers are thus fixed stationarily to the floor bars. The horizontal legs of the hangers are inclined toward each other near their forward 70 ends as shown at 21, and form attaching means for the vertically movable beam hereinafter described. Upwardly inclined braces 22 loosely engage the axle at their lower ends, and extend forwardly beyond the floor 75 bars, and are connected by a stand link 23 to a draft pole 24 the rear end of which is bolted or otherwise secured to the foremost cross beam 18 of the floor bars. Upon this frame just described, the beet digging, 80 carrying and topping mechanisms are supported.

The beet digging mechanism comprises a beam formed of two parallel horizontal bars 25, the rear ends of which are pivotally secured by means of pivot bolts 25' to the in-turned free ends 21 of the hangers, and the free ends of which are bent outwardly from each other to form divergent bunching fingers 26 which gather the standing foliage of 90 the beets and bunch the same together prior to uprooting of the beets. A pair of depending bowed picking fingers 27 are secured at their upper ends to the bars 25 near the bights in the bunching fingers as most 95 clearly shown in Fig. 5, and serve to pick up the foliage lying upon the soil. Plows 33 are arranged in rear of the bunching and picking fingers and serve to uproot the beets.

It will be understood that as the machine 100 is advanced over the field, the bunched foliage of the beets will move along rearwardly between the bars 25 of the plow beam, until they pass out at the rear ends of the bars. Here the foliage is caught and 105 carried to a topping knife by a pivotally hung carrier mechanism which may be rocked downward at its intake end to conform to the pivotal movements of the plow beam.

110 The carrier mechanism consists substantially of a pair of angular bars 53 which

are provided with suitable bearings near their elbows for the reception of the axle 10. To the forward ends of the bars are fixed depending parallel bars 54. To the lower ends of the bars 53 and 54 are secured angle irons 55 upon which is supported a sheet iron base plate 56 of substantially the shape shown in Fig. 8. Upon this plate is supported the beet carrying mechanism, which 10 will be presently described. In order that the frame thus formed may be rocked bodily upon the axle as a pivot, bowed links 56' are fixed to the bars 53 as clearly shown in Fig. 4, and between the upper ends of these links 15 is inserted one end of a draw link 57 which in turn is connected to one leg of a bell crank lever 58 pivoted at its elbow on a shaft 45. The other leg of the bell crank lever is connected by a link 59 to an operating lever 60 which is pivoted to a notched segment 61 and is equipped with a spring latch 62 which engages this notched segment and permits of the rocking frame above described being locked to any desired position. 20

25 In order to guide the frame in its rocking movements each horizontal leg of the hanger 19 is equipped on its inner face with arcuate guide bars 63 between which works a lug 64 carried by the adjacent angle iron 55 of the frame. This construction is most clearly shown in Fig. 6.

Journalized in bearings 65 fixed to the upper bars of the rocking frame, are the ends of a shaft 66, one end of this shaft 30 being equipped with a pinion 67 which meshes with the driving gear 14. This shaft is equipped with spaced bevel gears 68. Connecting the upper bars of the swinging frame underneath the bevel gears is a cross 40 bar 69 in which are journalized the upper end portions of stand shafts 70, the upper ends of these shafts being equipped with bevel gears 72 which mesh with the bevel gears 68. The shafts are equipped adjacent to their 45 lower ends with pulleys 73. It will now be seen that during rotation of the driving gear the stand shafts will be rotated, regardless of the adjusted position of the rocking frame. The stand shafts form drivers for the endless belts which grip the beet foliage and carry the beets rearwardly along the base plate to the topping knife.

50 Fixed to the base plate 56 at its rear end are a pair of spaced angle iron brackets 74 which carry threaded pins 75, the latter extending in parallelism with the base plate and being manually advanced in the brackets through the instrumentality of crank handles 76 fixed to the pins. Each pin remote from its crank handle is equipped with a yoke formed of independent branches 77, between which is rotatably mounted a pulley 78, the axle 79 of the pulley extending through a slot 80 formed in the base plate. 55 It will thus be seen that each pulley is ad-

justable longitudinally of the base plate. Over the stand shaft pulleys 73, and pulleys 78 are trained endless belts 81, between which the foliage of the beets is gripped and carried back along the base plate, it being understood that a slot 82 is formed in the base plate from the leading end of the latter to nearly the rear end to permit of the beets depending below the base plate as they are carried rearwardly thereupon. By virtue of one of the pulleys of each endless belt being adjustably mounted on the base plate, the belts may be slackened or tautened to adjust the endless carriers to grip either luxuriant foliage or sparse foliage of beets. 70 75 Idlers 83 are arranged on the base plate and bear against the inner sides of the belts to normally maintain the belts spaced but a slight distance apart, these idlers being mounted on centrally pivoted levers 84 80 which are equipped with helical springs 85 for enabling the levers to yield in order to permit very luxuriant foliage being carried by the belts.

For topping the beets, a blade 86 is arranged below the base plate, and is equipped at its opposite ends with gudgeons 87 which work in slots 88 formed in links 89, these links being equipped at their upper ends with stems 90 which extend through orifices 95 in the base plate and are equipped with retaining nuts 91 that bear upon the top face of the base plate and rigidly anchor the links in position. Nuts 92 are threaded upon the gudgeons and bear against the outer faces 100 of the links, and by frictional engagement with the outer faces of the links anchor the topping blade in any adjusted position longitudinally of the links. The cutting edge of the blade is disposed near the rear end 105 of the slot in the base plate and serves to sever the foliage from the beets while the foliage is still gripped and being carried rearwardly by the endless belts. The beets and foliage discharged from the carriers 110 are gathered up by an upright worm elevator 95 and delivered into any suitable receptacle.

What is claimed, is:—

1. In a beet harvester, a main frame, a wheeled axle, a pair of angular bars each pivoted near the elbow on said axle, depending bars fixed to the forward ends of said angular bars, a sloping platform fixed to the lower ends of said depending bars and 120 to the rear ends of said angular bars and underlying and extending in front of and in rear of said axle, beet carrying mechanism on said platform, and means for rocking said angular bars on said axle whereby 125 to change the slope of said platform.
2. In a beet harvester, a main frame, a wheeled axle, a pair of angular bars each pivoted near the elbow on said axle, a platform suspended from said angular bars, con- 130

fronting endless belt carriers on said platform each including spaced pulleys and a belt trained over said pulleys, a transverse shaft operatively connected to and rotated by said axle, a bar connecting the forward ends of said angular bars below said transverse shaft, stand shafts connected to the forward pulleys of said endless carriers and journaled in said connecting bar, and miter

gear connections between said stand shaft 10 and said transverse shaft.

In testimony whereof, I affix my signature, in presence of two witnesses.

CHARLES L. SLADINSKA.
